UNITED STATES PATENT OFFICE.

HORACE W. HADLEY, OF ORANGE, MASSACHUSETTS, ASSIGNOR TO THE
NEW HOME SEWING MACHINE COMPANY, OF SAME PLACE.

BOBBIN-WINDER.

SPECIFICATION forming part of Letters Patent No. 268,662, dated December 5, 1882.

Application filed September 21, 1882. (No model.)

To all whom it may concern:

Be it known that I, HORACE W. HADLEY, of Orange, county of Franklin, State of Massachusetts, have invented an Improvement in Bobbin-Winders, of which the following description, in connection with the accompanying drawings, is a specification.

My invention relates to a bobbin-winder, and has for its object to automatically guide the thread being wound, so that it is laid evenly over the entire length of the bobbin.

The invention is embodied in a bobbin-winder in which the bobbin-actuating spindle is provided with a worm engaging a worm-gear which carries a mutilated or segmental pinion, which, in its continuous rotation alternately, engages racks on opposite sides of it, the said racks being connected with a lever having a thread-guiding eye in its end, and the said lever being oscillated back and forth at each revolution of the worm-gear and connected pinion.

Figure 1 is a front elevation of a bobbin-winder embodying this invention; Fig. 2, a rear elevation thereof, and Figs. 3 and 4 rear and front elevations of the double rack-bar and worm-gear, with its mutilated pinion detached, on a larger scale.

The bobbin-actuating spindle *a* to receive one end of the bobbin and the center *b* to receive the other end are mounted in a framework, *c*, such as commonly employed, and the said spindle is provided with a pulley, *d*, by which it and the bobbin receive their rotary movement from the driving-wheel of the sewing machine. The spindle *a* is provided with a worm, *e*, engaging the teeth of a worm-gear, *f*, pivoted on the shank of a screw, *f'*, mounted on the frame-work *c*. The said gear *f* is provided with a series of pins forming a segmen-

tal or mutilated pinion, *g*, the teeth of which alternately engage racks *h* and *h'* in the double rack-bar *i*, pivoted at 2 to a lever, *j*, itself being pivoted at 3 upon the frame-work *c*. The said lever *j* is provided at its upper end with an eye, *k*, into which the thread to be wound is inserted through a slot, *m*, the said bar *j*, with its eye *k*, constituting a thread-guide.

It will be seen that as the spindle *a* and gear *f* rotate continuously in one direction in winding the thread upon the bobbin the gear *g* will alternately engage the rack *h* and *h'*, giving the rack-bar *i* a uniform movement first in one and then in the other direction, and that the said movement will be imparted to the thread-guiding eye *k*, thus causing the thread to be wound in even layers throughout the entire length of the bobbin.

I claim—

1. The combination of the mutilated pinion and rack-bar for producing a reciprocating rectilinear from a continuous rotary motion with the actuating-spindle and thread-guide of a bobbin-winder, substantially as described.

2. The combination of the mutilated pinion, rack-bar, and thread-guide with the bobbin-actuating spindle, worm, and worm-gear, substantially as described.

3. The combination of the mutilated pinion and rack-bar, with the thread-guiding lever, provided with a thread-holding eye, substantially as described.

In testimony whereof I have signed my name to this specification in the presence of two subscribing witnesses.

HORACE W. HADLEY.

Witnesses:

FRANK HOWE,
G. A. MAYNARD.
